Primary Examiner — Kendra Leslie Hamilton*(74) Attorney, Agent, or Firm* — Kim and Lahey Law Firm, LLC; Seann P. Lahey(57) **CLAIM**

The ornamental design for a horseshoe, as shown and described.

DESCRIPTION

FIG. 1 is a top, rear perspective view of a horseshoe, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the horseshoe that form no part of the claimed design.
